UNITED STATES PATENT OFFICE.

ALBERT FRANKLIN FIELDS, OF ALHAMBRA, CALIFORNIA.

DESIGN FOR A GAME-CHART.

47,869.

Specification for Design. Patented Sept. 21, 1915.

Application filed July 2, 1915. Serial No. 37,777. Term of patent 14 years.

To all whom it may concern:

Be it known that I, ALBERT FRANKLIN FIELDS, a citizen of the United States, residing at Alhambra, in the county of Los Angeles and State of California, have invented a new, original, and ornamental Design for a Game-Chart, of which the following is a specification, reference being had to the accompanying drawings, forming a part thereof.

The figure is a plan view of a game chart showing my design.

I claim:

The ornamental design for a game chart, as shown.

ALBERT FRANKLIN FIELDS.

Witnesses:

J. C. LADEVEZE,
FREDK. GRANT.
